(57) **CLAIM**

The ornamental design for an exercise platform, as shown and described.

DESCRIPTION

FIG. 1 is a first perspective view of an exercise platform showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a first perspective view shown in a state of use; and, FIG. 10 is an enlarged view of the selected portion 10 in FIG. 1.

The broken lines shown in the drawings depict portions of the exercise platform that form no part of the claimed design. The dash-dot-dash broken lines in FIGS. 1 and 10 depict the bounds of the enlarged view and form no part of the claimed design.
